CLAIM

The ornamental design for a camera, as shown and described.

DESCRIPTION

FIG. 1 is a front perspective view of a first embodiment of a camera illustrating my new design;

FIG. 2 is a front view of the first embodiment of FIG. 1;
FIG. 3 is a rear view of the first embodiment of FIG. 1;
FIG. 4 is a left side view of the first embodiment of FIG. 1;
FIG. 5 is a right side view of the first embodiment of FIG. 1;

FIG. 6 is a top view of the first embodiment of FIG. 1;
FIG. 7 is a bottom view of the first embodiment of FIG. 1;
and,

FIG. 8 is a front view of the first embodiment of FIG. 1, shown in condition of use and coupled with an illuminating mount disclosed in broken lines to illustrate an environment. The broken lines depict portions of the camera in which the design is embodied that form no part of the claimed design. Additionally, the dash-dot lines showing an illuminating mount in FIG. 8 represent environmental structure and form no part of the claimed design.

A second embodiment of a camera is a mirror image of the first embodiment of FIGS. 1–8.
